(No Model.)

D. GENESE & A. SCHMIDT.
CAR COUPLING.

No. 449,876.

Patented Apr. 7, 1891.

Fig. 1.

UNITED STATES PATENT OFFICE.

DAVID GENESE AND ADAM SCHMIDT, OF BALTIMORE, MARYLAND.

CAR-COUPING.

SPECIFICATION forming part of Letters Patent No. 449,876, dated April 7, 1891.

Application filed September 3, 1890. Serial No. 363,854. (No model.)

To all whom it may concern:

Be it known that we, DAVID GENESE and ADAM SCHMIDT, citizens of the United States, residing at Baltimore, State of Maryland, 5 have invented new and useful Improvements in Car-Couplings, of which the following is a specification.

This invention relates to that class of car-couplings in which a hook on one draw-head 10 is adapted to become automatically engaged with a slotted projection on the opposing draw-head and provided with means for holding said hook in an inoperative position and for actuating it in such manner as to uncouple 15 the cars from either side or from the car top or platform.

The invention consists in the construction and combination of parts in an automatic car-coupling, as hereinafter more fully described, 20 and then pointed out in the claims.

In the annexed drawings, illustrating the invention, Figure 1 is a perspective of one of our improved draw-heads and the coupling devices. Fig. 2 is a transverse vertical section of the same viewed from the rear. Fig. 3 is a longitudinal vertical section of the same. Fig. 4 is a horizontal section of the two draw-heads coupled. Fig. 5 is a perspective of a link device for use in connecting with 25 a car having the ordinary pin-coupling. Fig. 6 is a plan of a modified device for coupling by means of a pin and link.

Referring to the drawings, the numeral 1 designates a draw-head having a substantially 35 rectangular interior. One side of the lower wall of the draw-head 1 is provided with a forward projection 2, having a longitudinal slot 3, and provided with an upward and rearward inclined nose 4, that overhangs the forward portion of said slot and forms a shoulder 5, for engaging a hook on the opposite draw-head, as hereinafter explained. Adjacent to the projection 2 is a recess 6, formed 40 partly in the front portion of the lower wall of the draw-head and partly in the front lower portion of one of its side walls to afford space for the slotted projection on the opposing draw-head when the cars are coupled.

In the upper portion of each draw-head is 50 pivoted a coupling-hook 7 to engage the slotted projection 2 of the opposite draw-head.

Each hook 7 is formed with a tubular transverse body portion 8 to receive a pivot-pin 9, which is journaled at its ends in the opposite sides of the draw-head, a screw 10 being employed to rigidly connect said pin 9 and tubular body 8 of the hook, so that by withdrawing said screw the pin can be disengaged and drawn out at either side and permit the removal and replacement of the hook. The tubular hook-body 8 is of such length as to fit 55 between the opposite sides of the draw-head in a manner to prevent lateral displacement of the hook without interfering with its vertical oscillation or vibration in coupling and uncoupling.

On the rear side of the hook-body 8 is a lug or projection 11, on the under side of which bears the headed upper end of a vertical pin 12, that is supported in a vertically-adjustable 60 sleeve 13, secured in the lower rear portion of the draw-head. The pin 12 is surrounded by a spiral spring 14, which has a bearing at its lower end on the sleeve 13 and at its upper end bears against the under side of the pin-head, which in turn forces the projection 11 upward and so presses the hook 7 down into position for engagement with the slotted and shouldered projection 2 of the corresponding draw-head on the adjoining car. By loosening a nut 15 on the screw-threaded exterior of the sleeve 13, said sleeve can be adjusted vertically by means of a wrench to regulate the tension of the spring 14, as may be required. When two opposing draw-heads of this construction come together in the act of coupling, 65 the hook 7 of each draw-head rides over the pward an 1 rearward inclined nose 4 of the projection 2 on the other draw-head and becomes automatically engaged with the slot 3 70 and shoulder 5 under the action of the spring 14, which exerts sufficient force to maintain the parts in secure engagement until it is desired to uncouple the cars.

The rear upper portion of the draw-head is 75 provided with a slot 16 for passage of a laterally-swinging lever 17, that is pivotally supported between lugs 18, arranged in front and rear of said slot. The lower end of this lever 17 is bifurcated or provided with lateral downward and outward extended arms 19, adapted 80 to act on the upper cam-shaped or double-in-

clined surface 20 of the projection 11 for the purpose of raising the hook 7 from engagement with the slotted and shouldered projection 2 and for holding or locking the said hook 5 in an elevated position when required, so that it will not engage an opposing draw-head. The lever 17 may be operated from either side of the car or from its top or platform by means of suitable rods or levers 21, connected with the 10 upper end of the lever 17 and arranged in any convenient and appropriate manner for ready manipulation without passing between the cars.

While the cars are coupled the lever 17 15 hangs in a vertical position with its arms 19 on the opposite sides of the projection 11 without exerting any pressure thereon. In order to uncouple, it is only necessary to draw or push the upper end of the lever 17 to one 20 side, thereby causing one of its arms 19 to ride upward onto one of the inclined upper surfaces of the projection 11, so as to depress said projection, and consequently raise the hook 7 sufficiently to disengage it from the 25 projection 2 of the other draw-head. If it is desired to lock the hook 7 in an elevated position, so that it can be held from engagement with another draw-head, the movement of the lever 17 will be continued until an arm 19 30 bears on the flattened apex 22 of the projection 11, while the other arm 19 of said lever serves as a stop against the upper wall of the draw-head to prevent the lever 17 being tilted too far. While the hooks 7 of the opposing 35 draw-heads are in this elevated and locked position cars can be safely brought in close contact with each other without liability of coupling. When the hook 7 is raised, the pin 12 is depressed, thereby compressing the spring 40 14, which immediately throws the hook down into operative position as soon as the projection 11 is relieved from pressure by again throwing the lever 17 into a vertically-dependent position.

45 In the lower wall of each draw-head is a buffer 23, of any suitable construction, to take up the shock of the opposite projection 2 on the other draw-head when the cars come forcibly together. It will be observed that 50 the hooks 7 are each curved backward and provided with beveled faces to facilitate engagement with the slotted and shouldered projections 2 of the respective draw-heads.

The various parts of the coupling are so 55 proportioned and arranged in such relation to each other as to allow for reasonable variations in the height of the draw-heads of adjacent cars, which can thus be readily coupled though not of the same height, while the construction of the draw-heads and their attachments is such as to permit free play of the parts in all required directions without liability of disengagement under strain and jars.

For the purpose of connecting with cars not 60 fitted with this coupling, but having draw-heads provided with the ordinary coupling-pin, we propose to use a link 24, having in

one end a slot 25 for engaging said pin of the ordinary draw-head and provided at the other end with a depending arm 26, of any suitable 70 length, to enter the slot 3 of the projection 2, and preferably provided in front and rear with notches 27 at different heights to engage the shoulder 5 and the rear end of the slot 3, respectively.

75 Instead of the link 24 we may pivot on the ends of the hook-pin 9 a depending bail 27, provided with a link 28, adapted to be engaged with an ordinary coupling-pin on another car when said pivoted bail is raised to 80 a substantially horizontal position.

Either the link 24 or bail 27 can be provided for use in coupling with foreign cars or in an emergency incident to breakage.

85 The parts of our improved automatic coupling are few and simple, of durable and inexpensive construction, and can be readily repaired or replaced when required. It will also be observed that should either of the hooks 7 become broken or disabled while in 90 use the other will be sufficient to maintain the coupling. We would have it understood that these hooks 7 should be sufficiently heavy to operate effectively even without the aid of the springs 14, so that said springs can be 95 omitted, if desired, or, if retained, they may be arranged in any suitable or convenient manner.

100 It will be observed that if by any accident a car should overturn it will readily become uncoupled from adjoining cars, and so lessen the liability of pulling them from the track.

What we claim as our invention is—

105 1. In an automatic car-coupling, the combination, with a draw-head having on one side a slotted and shouldered forward projection and a hook pivoted in said draw-head to engage a corresponding slotted and shouldered projection of an opposing draw-head, of a depending laterally-swinging lever pivoted in the rear of the draw-head to depress and lock the rear end of said hook, with its forward end in an elevated position, substantially as described.

110 2. In an automatic car-coupling, the combination, with a draw-head having on one side a slotted and shouldered forward projection and a hook pivoted in said draw-head to engage a corresponding projection of an opposing draw-head, of a vertical spring-pressed 115 pin located beneath the rear end of said hook to throw the forward end down into operative position and a depending laterally-swinging lever pivoted in the rear of the draw-head to depress the rear end of said hook and elevate 120 its forward end, substantially as described.

125 3. In an automatic car-coupling, the combination, with a draw-head having on one side a slotted and shouldered forward projection and provided on the other side with an elastic 130 buffer, of a hook pivoted in said draw-head and provided with a rearward projection, a vertical spring-pressed pin located beneath and bearing on said projection to throw down the for-

ward end of the hook, and a depending laterally-swinging lever pivoted in the rear of the draw-head to depress the rear end of said hook and elevate the forward end, substantially as described.

4. In an automatic car-coupling, the combination, with a draw-head having on one side a slotted and shouldered forward projection and a hook pivoted in said draw-head and provided in rear of its pivotal point with a rearward-projecting lug having an inclined upper surface, of a vertical spring-pressed pin located beneath and bearing on said lug or projection to throw down the forward end of the hook and a depending laterally-swinging lever having arms to engage and depress said lug against the action of the spring-pressed pin and elevate the forward end of the hook, substantially as described.

5. In an automatic car-coupling, the combination, with the draw-head 1, having the slotted and shouldered projection 2 and recess 6, of the pivoted hook 7, having tubular body-portion 8 and lug 11, the pivot-pin 9, the vertical spring-pressed pin 12, located beneath and bearing on the lug 11, and the depending laterally-swinging lever 17, substantially as described.

6. In an automatic car-coupling, the combination, with the draw-head 1, having slotted and shouldered projection 2, recess 6, and buffer 23, of the pivoted hook 7, having lug

11, provided with upper double-inclined surfaces 20 and flattened apex 22, the vertical spring-pressed pin 12, and the depending laterally-swinging lever 17, provided with arms 19, substantially as described.

7. In an automatic car-coupling, the combination, with a recessed draw-head 1, having a forward projection 2, provided with slot 3, inclined nose 4, and shoulder 5, of the pivoted spring-pressed hook 7 and the depending laterally-swinging lever 17, substantially as described.

8. In an automatic car-coupling, the combination, with the recessed draw-head 1, having the slotted and shouldered forward projection 2 and pivoted hook 7, provided with lug 11, of the vertical pin 12, the adjustable sleeve 13, the spring 14, the nut 15, and the depending laterally-swinging lever 17, substantially as described.

9. In a car-coupling, the combination, with the draw-head 1, having slotted forward projection 2, of the link 24, provided with slot 55 25 and arm 26, substantially as described.

In testimony whereof we have affixed our signatures in presence of two witnesses.
